DESCRIPTION

FIG. 1 is a front elevational view of a glass funnel for a cathode ray tube, showing my new design, the rear view being a mirror image of the front view shown;

FIG. 2 is a top plan view thereof;

FIG. 3 is a bottom plan view thereof;

FIG. 4 is a right side elevational view thereof, the left side elevational view being a mirror image of the side view shown;

FIG. 5 is a cross-sectional view taken along line V—V of FIG. 2; and,

FIG. 6 is a cross-sectional view taken along line VI—VI of FIG. 2.
